UNITED STATES PATENT OFFICE.

JOHN P. ODGERS, OF PHILADELPHIA, PENNSYLVANIA, ASSIGNOR TO THE
A. M. COLLINS MANUFACTURING COMPANY, OF SAME PLACE.

DESIGN FOR A CARD-MOUNT.

SPECIFICATION forming part of Design No. 32,569, dated April 24, 1900.

Application filed March 30, 1900. Serial No. 10,849. Term of patent 7 years.

To all whom it may concern:

Be it known that I, JOHN P. ODGERS, a citizen of the United States, residing in Philadelphia, Pennsylvania, have invented a certain 5 new and original Design for a Card-Mount, of which the following is a specification.

My design for a card-mount is fully illustrated in the accompanying drawings, in which—

10 Figure 1 is a face-view of the card-mount, and Fig. 2 is an enlarged sectional view.

The essential feature of the design is the card-mount having a background consisting of a series of parallel lines or ribs.

15 A is the panel for the photograph, and surrounding the same is a plain band B, and be-

tween the band and the edge of the card is the background D, having a series of parallel indentations a, forming ribs b, as illustrated in Fig. 2.

I claim—

The design for a card-mount as herein described and as illustrated in the accompanying drawings.

In testimony whereof I have signed my 25 name to this specification in the presence of two subscribing witnesses.

JOHN P. ODGERS.
